UNITED STATES PATENT OFFICE.

JOHN BEISWANGER, OF STEUBENVILLE, OHIO.

DESIGN FOR A LAMP-SHADE.

47,321.

Specification for Design.

Patented May 11, 1915.

Application filed March 3, 1915. Serial No. 11,873. Term of patent 7 years.

To all whom it may concern:

Be it known that I, JOHN BEISWANGER, a citizen of the United States, residing at Steubenville, in the county of Jefferson and State of Ohio, have invented a new, original, and ornamental Design for Lamp-Shades, of which the following is a specification, reference being had to the accompanying drawings, forming part hereof, in which the several parts are indicated by numerals, like parts being indicated by like numerals.

Figure 1 is a front elevation of the lamp shade as viewed from the point 2, Fig. 3. Fig. 2 is a second front elevation as viewed on the line 4—4 of Fig. 3. Fig. 3 is a top plan view. Fig. 4 is a vertical section taken on the line 4—4 of Fig. 3. Fig. 5 is a bottom plan view.

The lamp shade which is the subject of this design is a concavo-convex structure adapted to be suitably mounted in connection with any source of illumination, so as to shield the eye from direct rays of light. It may be made of any suitable material, preferably however of such materials as are translucent.

The structure of the article may be described as follows: It is provided with three annular sections such as 1, 2 and 3. Intermediate of the sections 1 and 2 is the annular depression 4. Four smooth faces are provided between the annular members 2 and 3, which are indicated as 5, and inter-

mediate said faces 5 are the depressions 6, preferably V-shaped in cross section and running between the points 7 and 8. These depressions 6 are radial to the axis of the shade, each depression 6 being at right angles to two of the other depressions of the same number. 9 is an annular aperture communicating at the top end thereof with the concave aperture 10, and at the other end thereof with the concave interior of the shade indicated as 11. 12 designates an annular bend in the face 5 at the lower end thereof, and 13 the annular bend at the upper end thereof. The faces 5 are smooth between the depressions 6—6, the same being slightly convex on the exterior thereof as indicated at 14. The depressions 6 are preferably V-shaped in cross section as indicated. In the drawing Fig. 4, the shade is cut on the lines 4—4, thus exhibiting the terminal points of the depressions 6 as indicated at 7 and 8, where they taper to a vanishing point. The shade is preferably of uniform thickness, the external and internal surfaces corresponding substantially.

What I claim is:

A design for a lamp shade as shown and described.

Signed by me at the city of New York, N. Y. this 2nd day of March 1915.

JOHN BEISWANGER.

Witnesses:

C. D. EDWARDS,
MARGARET VOGEL.
